UNITED STATES PATENT OFFICE.

THOMAS J. DOWD, OF NEW YORK, N. Y.

ADJUSTABLE TAP AND DIE.

Application filed August 31, 1922. Serial No. 585,395.

To all whom it may concern:

Be it known that I, THOMAS J. Dowd, a citizen of the United States, residing at New York, in the county of New York and State 5 of New York, have invented certain new and useful Improvements in an Adjustable Tap and Die; and I do hereby declare the following to be a full, clear, and exact description of the invention, such as will enable 10 others skilled in the art to which it appertains to make and use the same.

The object of the invention is to provide a convertible tap and die of which the bit designed for joint action upon the object to be 15 threaded internally or externally may be adjusted simultaneously and accurately within a relatively wide range of movement; and with this object in view the invention consists in a construction, and relation of parts 20 of which a preferred embodiment is illustrated in the accompanying drawing, wherein:

Figure 1 is a side view partly broken away of a tool embodying the invention with the 25 parts arranged as a tap.

Figure 2 is a plan view of the same.

Figure 3 is a reverse or bottom plan view thereof,

Figure 4 is a transverse or axial sectional 30 view thereof,

Figure 5 is a plan view with the upper retainer disk omitted,

Figure 6 is a section on the plane indicated by the line 6—6 of Figure 4.

Figures 7 and 8 are detail views of the 35 members of one of the tapping bits,

Figures 9 and 10 are respectively plan and side views of the tool arranged for use as a die,

Figures 11 and 12 are sectional views respectively on the planes indicated by the line 11—11 of Figure 10 and 12—12 of Figure 9,

Figure 13 is a detail view of one of the die bits,

Figure 14 is a detail sectional view on the plane indicated by the line 14—14 of Figure 2.

The tool consists essentially of an annular head or body 20 provided with radially extending operating arms 21 and carrying bit shanks which, in the adjustment of the elements indicated in Figures 1 to 6 inclusive are shown at 22 and are fitted in radial guides 23 with their inner ends projecting 55 into the central opening of the head or body

to carry cutter heads which in the arrangement shown in Figures 1 to 6 are indicated at 24 and consist of toothed bars which extend in a direction parallel with the axis of the head and are movable by the shanks 60 toward and from the axis of the head within a range of movement determined by the radius of the opening therein.

These bit shanks are provided with racks 65 with which mesh pinions 26 mounted in the head with their axes parallel with the axis of the head, and they are simultaneously

actuable to cause a mutual and equal adjustment inwardly or outwardly of the bit shanks by means of a revolute adjusting 70 ring 27 mounted upon and parallel with the head in coaxial alignment therewith and provided with an exterior milled periphery which projects sufficiently beyond the periphery of the head to be engaged by the 75 fingers of the operator in effecting the adjustment of the shanks. The pinions are

held in place in the terminally open bearings in the head or body by means of opposite lower and upper retaining disks 28 and 29 80

secured in place by retaining screws 30 which pass through the head or body, a cross sectionally angular bushing 31 being fitted in the upper or outer retaining disk as shown clearly in Figure 4 to afford a bearing space 85

for the adjusting ring 27 which surrounds the body portion thereof. By the removal of the lower retaining disk as will be obvious the pinions may be displaced. The 90

upper retaining disk is provided with an index notch 31' with which cooperates a graduated scale 32 on the adjusting ring as a means of indicating the position of the bits controlled by the said ring and as a guide to the operator in setting the bits, and to 95

secure the adjusting ring in its adjusted positions there is employed the set screw 33 carried by the upper retainer.

In the form of the tool which is designed particularly for tapping work the body portion of the head preferably consists of the main disks 34, from which project the operating arms 21, and a supplemental disk 35, preferably keyed together by a pin 36

carried by one of said disks (preferably the supplemental disk as shown) and the bit shank 22 is supplemented by an auxiliary bit shank 22' operating in a guide 37 in the 100 supplemental disk and provided at its inner end with a sleeve 24' grooved to receive the 105

supplemental disk and provided at its inner end with a sleeve 24' grooved to receive the 110

cutter bar 24 to reinforce the latter against transverse deflection or displacing strain in the operation of the tool, the edges of said sleeve at the face of the cutter being beveled 5 as shown at 38 to avoid any interference with the action of the cutter.

Also to further reinforce the tapping bits, each of which as above indicated consists of cooperating members consisting of main and 10 auxiliary shanks (both of which carry racks for engagement by the motion transmitting pinions 26) and the former of which carries the cutter 24 nested in the protective sleeve 24', it is preferred to employ reversely disposed conical spreaders 39 and 40 fitted between the tapping bits at the upper and lower or outer and inner ends of the cutting elements thereof and connected by a threaded adjusting rod 41 having a terminal milled 15 head 42 and engaged by a nut 43, the conical surfaces of these spreaders being longitudinally grooved as shown respectively at 39^a and 40^a to seat the adjacent ends of the cutting elements of the bits to prevent vibration thereof in the operation of the tool.

In the adjustment of the members of the tool to adapt it to perform the functions of a thread cutting die, as indicated in Figures 9 to 13 inclusive, the auxiliary body disk of 20 the head is preferably omitted and the head consists of the single disk 34^a, corresponding with and in fact being the same disk as that designated 34 in the adjustment indicated in Figures 1 to 6 inclusive, and carrying the 25 operating arms 21^a, the bit shanks 22^a which are provided at their inner ends with the die cutters 24^a having the rack teeth 25^a for engagement by pinions 26^a engaged as previously described by the adjusting ring 27^a 30 having internal gear teeth and being in embracing relation with the bushing 31^a, associated with the inner and outer retainer disks 28^a and 29^a secured together by the retaining screws 30^a.

45 The tool as shown in Figures 1 to 6 of the drawings is set for operation as a tap, upon the largest work upon which the tool may be used. To set the tool for use as a tap for operation on a small job, the cones 50 39 and 40 are moved apart by operating the screw 41 and the bit shank 22 and cutter head 24 carried thereby may then be moved toward the axis of the head the required distance, by rotating revoluble adjusting ring 27 which turns the pinions 26 in mesh 55 with the racks 25 provided on the bit shanks 22. When the bit shanks and cutter heads have been adjusted, the cone blocks 39 and 40 may be moved to and locked in 60 a position to engage the outer terminals of the cutter heads and brace the same. The auxiliary bit shanks 22' and the sleeves 24' are moved simultaneously with the bit shanks 22 and the cutter heads 24. When 65 the tool is assembled for use as a die as

shown in Figures 9 to 12, the bit shanks 22^a may be adjusted toward or away from the axis of the head or disk 34^a by rotating the revoluble adjusting ring 27^a in a counter clockwise or in a clockwise direction. The 70 bit shanks 22^a and part carried thereby are adjusted toward the axis of the head 34 by movement of the ring 27^a in a counter clockwise direction and are moved away 75 from the axis of the head by movement of the ring 27 in a clockwise direction. The tool may be rotated by grasping and turning the handle members 21 or 21^a according to the former tool being used.

It will be obvious that the conversion of 80 the tool from a tap to a die can be effected readily, merely upon the loosening of the retaining screws which serve as the means for securing the retainer disks in their proper positions and which in turn hold the 85 intermediate elements of the structure in their proper relations, and that a variety of bits adapted for different purposes and designed to form threads of different pitch and gage may be interchangeably used in 90 this connection.

It will further be understood that the tool is susceptible of a wide range of modification in the matter of dimensions and particularly of the diameter of the head 95 and the opening therein to afford a range of movement of the bit cutters.

Having thus described the invention, what I claim is:—

1. A threading tool having an annular 100 head provided with radial guides, bit shanks fitted in the guides and having rack teeth, said bit shanks carrying tapping cutter bars extending parallel with the axis of the head, pinions mounted in the head in mesh with the rack teeth of the bit shanks, and a revoluble adjusting member mounted upon the head for communicating simultaneous rotary movement to said 105 pinions.

2. A threading tool having an annular head provided with radial guides, bit shanks fitted in the guides and having rack teeth, said bit shanks carrying tapping cutter bars extending parallel with the axis of the head, pinions mounted in the head in axial 115 perpendicularity to the paths of the shanks and meshing with the racks thereof, and a revoluble adjusting ring mounted on the head in mutual meshing relation with said 120 pinions.

3. A threading tool having an annular head provided with radial guides, bit shanks fitted in the guides and having rack teeth, said bit shanks carrying tapping 125 cutter bars extending parallel with the axis of the head, pinions mounted in the head in axial perpendicularity to the paths of the shanks and meshing with the racks thereof, and an internally toothed adjust- 130

ing ring mounted upon the head in axial parallelism with the pinions and meshing mutually therewith.

4. A thread cutting tool having a head 5 consisting of a body disk provided with radial operating arms and oppositely disposed retainer disks connected by retaining screws extending through the body disk, bit shanks fitted in radial guides in the body 10 disk and provided with rack teeth, pinions mounted in openings in the body disk and in mesh with the racks of the shanks, said pinions being terminally confined by the retainer disks, and a common adjusting ring 15 revolvably mounted upon the head in internal meshing relation mutually with said pinions for effecting simultaneous adjustments of the bit shanks.

5. A thread cutting tool having a head 20 consisting of a body disk provided with radial operating arms and oppositely disposed retainer disks connected by retaining screws extending through the body disk, bit shanks fitted in radial guides in the body 25 disk and provided with rack teeth, pinions mounted in openings in the body disk and in mesh with the racks of the shanks, said pinions being terminally confined by the retainer disks, and a common adjusting ring 30 revolvably mounted upon the head in internal meshing relation mutually with said pinions for effecting simultaneous adjustments 35 of the bit shanks, tapping cutter bars being carried by the inner end of the bit shanks in parallelism with the axis of the head.

6. A thread cutting tool having a head 40 consisting of a body disk provided with radial operating arms and oppositely disposed retainer disks connected by retaining screws extending through the body disk, bit shanks fitted in radial guides in the body disk and provided with rack teeth, pinions mounted in openings in the body disk and in 45 mesh with the racks of the shanks, said pinions being terminally confined by the retainer disks, and a common adjusting ring revolvably mounted upon the head in internal meshing relation mutually with said pinions for 50 effecting simultaneous adjustments of the bit shanks, tapping cutter bars being carried by the inner ends of the bit shanks, in combination with supplemental bit shanks actuatable by said pinions and having sleeves 55 for housing said cutter bars.

7. A thread cutting tool having a head 60 consisting of a body disk provided with radial operating arms and oppositely disposed retainer disks connected by retaining screws extending through the body disk, bit shanks fitted in radial guides in the body disk and provided with rack teeth, pinions mounted in openings in the body disk and in 65 mesh with the racks of the shanks, said pinions being terminally confined by the re-

tainer disks, and a common adjusting ring revolvably mounted upon the head in internal meshing relation mutually with said pinions for effecting simultaneous adjustments of the bit shanks, tapping cutter bars being carried by the inner ends of the bit shanks, in combination with supplemental bit shanks actuatable by said pinions and having sleeves for housing said cutter bars, said sleeves having beveled outer edges for exposing the cutting faces of said bars.

8. A thread cutting tool having a head consisting of a body disk provided with radial operating arms and oppositely disposed retainer disks connected by retaining screws extending through the body disk, bit shanks fitted in radial guides in the body disk and provided with rack teeth, pinions mounted in openings in the body disk and in mesh with the racks of the shanks, said pinions being terminally confined by the retainer disks, and a common adjusting ring revolvably mounted upon the head in internal meshing relation mutually with said pinions for effecting simultaneous adjustments of the bit shanks, the inner ends of the bit shanks being provided with cutter bars disposed in parallelism with the axis of the head, in combination with an auxiliary body disk, and shanks mounted in radial guides in said auxiliary disk and provided with rack teeth meshing with said pinions, the inner ends of the auxiliary shanks being provided with cutter bar protecting sleeves extending parallel with and seating said cutter bars.

9. A thread cutting tool having a head 105 consisting of a body disk provided with radial operating arms and oppositely disposed retainer disks connected by retaining screws extending through the body disk, bit shanks fitted in radial guides in the body disk and provided with rack teeth, pinions mounted in openings in the body disk and in mesh with the racks of the shanks, said pinions being terminally confined by the retainer disks, and a common adjusting ring revolvably mounted upon the head in internal meshing relation mutually with said pinions for 110 effecting simultaneous adjustments of the bit shanks, said bit shanks carrying tapping cutter bars extending parallel with the axis of the head, in combination with reinforcing means consisting of oppositely directed conical spreaders interposed between opposite ends of the cutter bars and connected by an adjusting rod.

10. A thread cutting tool having a head 125 consisting of a body disk provided with radial operating arms and oppositely disposed retainer disks connected by retainer screws extending through the body disk, bit shanks fitted in radial guides in the body disk and provided with rack teeth, pinions mounted in openings in the body disk and in mesh with the racks of the shanks, said pinions being terminally confined by the re-

the racks of the shanks, said pinions being terminally confined by the retainer disks, and a common adjusting ring revolvably mounted upon the head in internal meshing relation 5 mutually with said pinions for effecting simultaneous adjustments of the bit shanks, said bit shanks carrying tapping cutter bars extending parallel with the axis of the head, in combination with reinforcing means consisting of oppositely directed conical spreaders interposed between opposite ends of the cutter bars and connected by an adjusting rod, said rod being provided at one end with a milled head and being engaged by a lock 10 nut.

11. A thread cutting tool having a head consisting of a body disk provided with radial operating arms and oppositely disposed retainer disks connected by retaining 20 screws extending through the body disk, bit shanks fitted in radial guides in the body disk and provided with rack teeth, pinions mounted in openings in the body disk and in mesh with the racks of the shanks, said pinions 25 being terminally confined by the retainer disks, and a common adjusting ring revolvably mounted upon the head in internal meshing relation mutually with said pinions for effecting simultaneous adjustments of the bit 30 shanks, said bit shanks carrying tapping cutter bars extending parallel with the axis of the head, in combination with reinforcing means consisting of oppositely directed conical spreaders interposed between opposite 35 ends of the cutter bars and connected by an adjusting rod, said spreaders being pro-

vided with side longitudinally disposed channels for seating the extremities of said cutter bars.

12. A threading tool having an annular head provided with radial guides, bit carrying shanks fitted in the guides, said bit carrying shanks carrying tapping cutter bars, a revolvable adjusting member mounted on the head, and means for communicating motion from said member to the bit shank, in combination with reinforcing means consisting of oppositely directed conical spreaders interposed between opposite ends of the cutter bars and connected by an adjusting 50 rod.

13. A threading tool having an annular head provided with radial guides, bit shanks fitted in the guides, said bit shanks carrying tapping cutter bars extending parallel with the axis of the head, a revolvable adjusting member mounted on the head, and means for communicating motion from said member to the bit shanks, in combination with reinforcing means consisting of oppositely directed conical spreaders interposed between opposite ends of the cutter bars and connected by an adjusting rod, said spreaders being provided with side longitudinally disposed channels for receiving the extremities 60 of said cutter bars.

In testimony whereof I affix my signature in presence of two witnesses.

THOMAS J. DOWD.
